US00D921013S

(12) United States Design Patent (10) Patent No.: US D921,013 S
(45) Date of Patent: * Jun. 1, 2021

(54) DISPLAY SCREEN OR PORTION THEREOF WITH GRAPHICAL USER INTERFACE

(71) Applicant: Aristocrat Technologies Australia Pty Limited, North Ryde (AU)

(72) Inventor: Eric Steven Boese, Decatur, GA (US)

(73) Assignee: ARISTOCRAT TECHNOLOGIES AUSTRALIA PTY LIMITED

() Term: 15 Years

(21) Appl. No.: 29/709,002

(22) Filed: Oct. 10, 2019

CLAIM

The ornamental design for a display screen or portion thereof with graphical user interface, as shown and described.

DESCRIPTION

FIG. 1 is the front view of a display screen or portion thereof with graphical user interface showing my new design according to a first third embodiment;

FIG. 2 is the front view of a display screen or portion thereof with graphical user interface showing my new design according to a second embodiment;

FIG. 3 is the front view of a display screen or portion thereof with graphical user interface showing my new design according to a third embodiment; and,

FIG. 4 is the front view of a display screen or portion thereof with graphical user interface showing my new design according to a fourth embodiment.

The dashed broken line perimeter in the figures illustrates a display screen or portion thereof and forms no part of the claimed design. The remaining dashed broken lines in the figures illustrate portions of the graphical user interface that form no part of the claimed design.

1 Claim, 4 Drawing Sheets
